UNITED STATES PATENT OFFICE.

CHARLES W. HUBBARD, OF WESTON, MASSACHUSETTS.

STOP MOTION.

Application filed May 19, 1923, Serial No. 640,111. Renewed November 20, 1925.

This invention relates to stop motions for drawing frames, roving frames or machines of like nature and it has for its general object to provide a novel stop motion which is simple in construction and positive and efficient in operation and which further assists the passage of the sliver as it traverses through the stop motion rather than retards it and which has various other advantageous features all as will be more fully hereinafter set forth.

In order to give an understanding of the invention I have illustrated in the drawings a selected embodiment of the invention which will now be described after which the novel features will be pointed out in the appended claims.

Fig. 1 is a plan view of a portion of a roving machine showing my improved stop motion;

Fig. 2 is an enlarged section on the line 2—2, Fig. 1;

Fig. 3 is a similar view showing the sliver broken and the stop motion in operation;

Fig. 4 is a diagrammatic view illustrating the application of my invention to a drawing frame.

Inasmuch as the invention relates simply to the stop motion I have not illustrated in the drawings a complete drawing frame or roving frame and in fact have only shown a sufficient portion of such a machine to enable the invention to be understood.

In Fig. 4 some of the essential parts of a drawing frame are illustrated diagrammatically, 60 being the can from which the sliver 50 is withdrawn, 61 being the usual retaining rolls to which the sliver is delivered from the can and 62 being the drawing rolls through which the sliver passes and which operate to perform the drawing operation.

My improved stop motion is situated between the can or receptacle 60 and the retaining rolls 61 and it acts on the sliver 5 as it is delivered from the can 60. The operative parts of the machine are supported on a suitable frame 1, a portion only of which is shown in the drawings and such operative parts are driven through a suitable clutch or driving belt which is controlled by a shipling lever that is held in operative position against the pressure of a spring by a catch as is usual in machines of this character. When the catch is released the spring operates the shipling lever to throw the belt onto

the loose pulley or to disengage the clutch. This release of the catch is effected by a controlling rod all as usual and which is herein shown at 2, said rod normally having the position shown in Fig. 2 but being movable into the position shown in Fig. 3 thereby to release the catch and permit the spring to shift the belt to the loose pulley.

My improved stop motion comprises two long rolls or shafts 3, 4 which are separated from each other and are situated between the feed cans 60 and the back-retaining rolls 61 and in position so that the sliver 5 passes over these rolls or shafts as it travels from the cans 60 to the retaining roll 61. These rolls or shafts are shown as supported in suitable brackets 6 secured to the frame and means are provided for positively driving them.

The means herein shown for this purpose comprises gears 8 and 9 fast on the rolls 3 and 4 and both meshing with an intermediate driving gear 10. The rolls are positively driven from the shaft of the retaining rolls 61 and at the same surface speed, the result of which is that the positive driving rolls 3 and 4 help to lift the sliver out of the can.

These rolls 3 and 4 extend the full length of the machine so that each individual sliver 5 passes over the rolls as shown in Fig. 2. 11 indicate guides associated with the roll 3 and acting as guides for the sliver ends to hold them in proper position.

Co-operating with the rolls 3 and 4 are a series of weight rolls 12, there being one such weight roll for each sliver. These weight rolls are relatively short and each has a diameter equal to the distance between the rolls 3 and 4 so that if the weight rolls are unsupported they can pass freely between the rolls 3 and 4. These weight rolls are supported between rolls 3 and 4 by the presence of the sliver 5, each sliver extending over the roll 3, underneath its roll 12 and between the latter and the roll 4 and thence to the retaining rolls 61 and to the drawing, twisting and winding devices.

While the weight rolls 12 can pass freely between the rolls 3 and 4 when there is no sliver present yet when the sliver 5 is intact and is situated between the rolls 3 and 4 and the weight roll 12 it will support the roll 12 and hold it in the position shown in Fig. 2. Hence so long as any sliver is in

tact the corresponding weight roll 12 will be supported in the position shown in Fig. 2 but if the sliver runs out and is withdrawn from between the rolls 3 and 12 then the support for the weight roll 12 is removed and said roll will drop between the rolls 3 and 4 as shown in Fig. 3.

Means are provided whereby when any weight roll 12 thus drops between the rolls 3 and 4 the controlling rod 2 will be actuated to stop the machine. The means I have provided for this purpose comprises a rock shaft 13 extending longitudinally of the frame and having at one end an arm 14 adapted to engage a collar 15 carried by the rod 2 so that turning movement of the shaft 13 anti-clockwise in Fig. 2 will move the controller rod 2 to the left and release the spring acting on the shipping lever thereby to stop the machine.

The rock shaft 13 has rigid therewith a plurality of arms 16 which carry troughs or receptacles 17 that are situated beneath the rolls 12 and are adapted to receive the latter when they drop through the space between the rolls 3 and 4. The counter-shaft 13 is counterbalanced by a counterweight 18 which is hung on an arm 19 extending from the shaft and said weight is such that it just overbalances the weight of the arm 16 and trough 17 so that normally the parts are in the position shown in Fig. 2. Since the shaft 13 is just counterbalanced a slight downward pressure on the ends of the arms 16 will be sufficient to turn the shaft 13 anti-clockwise and thus shift the controlling rod 2 so as to release the spring and to stop the machine.

The weight rolls 12 are constructed so that the weight of any one of the rolls is sufficient for this purpose. Therefore, if any sliver runs out the corresponding weight rolls 12 will drop between the rolls 3 and 4 into the trough 17 thereby turning the rock shaft 13 as shown in Fig. 3 and operating through the arm 14 to actuate the controller rod 2 and stop the machine.

The machine is so arranged that the distance between the stop motion and the back-retaining roll 61 is sufficient to permit the machine to come to rest after the stop motion has acted and before the broken end of the sliver which has been drawn through the stop motion has reached the retaining rolls so that after the machine comes to rest there will always be a sufficient length of the sliver projecting from the retaining rolls to permit the sliver to be readily pieced up. After the stop motion has operated the weight roll 12 is removed from the trough, the sliver is pieced and then the weight roll is replaced in position on the sliver.

As stated above the rolls 3 and 4 are driven at a surface speed equal to that of the retaining rolls 61 so that said rolls as-

sist in lifting the sliver from the can and feeding it to the drawing rolls.

The apparatus herein illustrated is simple in construction but positive and efficient in operation.

The weight rolls 12 are held from movement longitudinally of the frame or in the direction of their axis by means of positioning arms 19, 20, the arms 19 being secured to a rod 21 carried by the bracket 6 and the arms 20 being carried by said brackets. These positioning arms retain the rolls 12 in proper position and will allow them to rotate freely and permit them to freely drop when the sliver runs out or is withdrawn between the rolls 3 and 4 and the weight roll 12 either because of exhaustion from the can 60 or because of breakage.

I claim:

1. In a stop motion, the combination with a pair of separated rolls over which the sliver passes, of means to rotate said rolls, a weight roll having a diameter equal to the distance between said driven rolls and resting on and supported by the sliver between said driven rolls whereby when the sliver runs out or breaks said weight roll will drop between said driven rolls, a rock shaft having arms, a trough supported by said arms and situated to receive the weight roll when the latter drops, and a controlling rod actuated by turning movement of the shaft due to the dropping of a weight roll.

2. In a stop motion, the combination with a pair of separated rolls over which the sliver passes, of means to drive said rolls, a plurality of weight rolls each having a diameter equal to the distance between said driven rolls and each resting on and supported by a sliver between said driven rolls, whereby when any sliver runs out or breaks the corresponding weight roll will drop between the driven rolls, a controller rod and means to actuate the controller rod by any weight roll when it drops between the driven rolls.

3. In a stop motion, the combination with a pair of separated rolls over which the sliver passes, of a weight roll having a diameter equal to the distance between said separated rolls and resting on and supported by the sliver between said rolls, whereby when the sliver runs out or breaks the weight roll will drop between the separated rolls, means to rotate the first-named rolls at a surface speed equal to that at which the sliver is drawn thereover, said rolls giving rotation to the weight roll by frictional contact, a controller rod by which the machine is stopped, and means to actuate the controller rod by a weight roll when it drops between the separated rolls.

4. In a stop motion, the combination with a pair of separated rolls over which the sliver passes, of a weight roll having a diameter equal to the distance between said sep-

- arated rolls and resting on and supported by the sliver between said rolls, whereby when the sliver runs out or breaks the weight roll will drop between the separated rolls, 5 means to rotate the first-named rolls at a surface speed equal to that at which the sliver is drawn thereover, said rolls giving rotation to the weight roll by frictional contact, a controller rod by which the machine 10 is stopped, a rock shaft, arms carried thereby, troughs supported by the arms and situated to receive the weight roll when it drops, and means to shift the controller rod by the turning movement of the rock shaft due to 15 a weight roll being received in the trough.

5. In a roving or similar machine having a feed can from which the sliver is withdrawn and positively-driven back-retaining

rolls for drawing the sliver from the can, the combination with said can and retaining 20 rolls, of a stop motion comprising a pair of supported rolls rotating at the same surface speed as the retaining rolls and situated between the can and said retaining rolls and over which the sliver passes, a weight roll 25 having a diameter equal to the distance between the separated rolls and resting and supported by the sliver between said rolls, whereby when the sliver runs out the weight roll will drop between the driven rolls, and a 30 controller rod actuated by the weight roll when the latter drops.

In testimony whereof, I have signed my name to this specification.

CHARLES W. HUBBARD.
